UNITED STATES PATENT OFFICE

2,271,455

CONTAINER

Harry W. Finn, Monroe, Mich., assignor to Consolidated Paper Company, Monroe, Mich., a corporation of Michigan

Application October 30, 1939, Serial No. 301,919

1 Claim. (Cl. 229—4.5)

This invention relates to receptacles from sheet stock.

This invention has utility in sealed substantial paper or fiber-walled cans adaptable to be coated with exposure to slight maximum flexure and resistant to internal and external load. These containers are suitable for receiving hot pourings of readily congealable material, such as bituminous matter. Asphalt as so handled may enter the vessel with the vessel retaining its form independent of external holding means or mold. Furthermore, there is opportunity for positioning the closure in sealing position independently, of the one performing such operation, being exposed to direct contact with the hot liquid.

Referring to the drawing:

Fig. 1 is a view of the scored cut blank for the body or main portion of the vessel or receptacle;

Fig. 2 is a view of the bottom head or disk 20 for the closure base;

Fig. 3 is a side elevation of the body of Fig. 1 stitched into tubular form and collapsed, or in the flat, for storage or ready supply to the place to be charged;

Fig. 4 is a side elevation, with parts broken away, of the charged container;

Fig. 5 is a plan view of the sealed top of the charged container of Fig. 4, involving the major tongues in edge overlapping relation;

Fig. 6 is a bottom plan view of the base of Fig. 4 in which the tongues marginally about as folded inward and are stitched to each other and the disk of Fig. 2; and

Fig. 7 is a view similar to Fig. 5, wherein the polygonal group of tongues is in octagon arrangement instead of hexagon as in Fig. 5.

Sheet stock as of paper board, fiber board, or box board, with the grain or general fiber direction approximately parallel to a line 1, gives rigidity to this main body for portions 2, 3, 4. The portion 3 is separated from the portion 1 by a score 5 and from the portion 4 by a score 6, parallel to each other. These scores 5, 6, intercept parallel scores 7, 8. The score 7 has therebeyond annular series of minor tongues 9 with V-cut outs 10 therebetween having short spacing 11 from the score line 7. The scores 5, 6, are medially of these trapezoidal tongues 9.

Remote from this series of minor tongues 9 is a series of major tongues 12 extending from the score line 8. These rectangular tongues 12, as the major tongues, have the major score lines 5, 6, extend therethrough. From the line 1 of the blank, major sectional tongue 13 has coop-

eration with minor tongue 14 as seam 15 effects closing of this main body into a tubular set-up. This seam 15 herein comprises sets of stitching 16 in closer or more effective holding proximity to each other adjacent the score line 7 and gradually opening out into wider stitch portions 17 toward the score line 8. This is a matter of economy in manufacture, in that the greater load strain near the base score line 7 has response in the closer stitching holding portion 16, while as the top portion is reached the more open stitching 17 is sufficient for positive holding and efficient sealing.

At assembly, this collapsed body folded on the score lines 5, 6, is opened out to have in such tube, a disk 18, which may more or less approach or depart from circular form. This disk 18 on its inside may have coating 19 as say the inside of the tubular body may be similarly coated. In the event there is use of the vessel with a substance tending to adhere to the stock, and which adherence it is wished to defeat, there is importance in selecting this coating. This importance lies not only for ready severance and thereby saving the full volume of the contents, but may be against soaking into or attacking of this body by the charge. In the instance of a product in which more difficulty has been experienced, hot asphalt, a coating has been adopted which will resist attack on the fiber or paper board by the hot asphalt. This coating will permit ready tearing of the paper clear of the asphalt as the asphalt is congealed. Forms of this coating substance are disclosed in applications for United States Letters Patent by Jackson H. Rollins and Walter E. Hatch: Ser. No. 232,015, filed Sept. 27, 1938, Coating; and Ser. No. 276,440, filed May 29, 1939, Special coating composition values.

With this disk 18 in position and its coating side 19 on the inward or upper side, the opposite or outer side of the disk 18 may have folded thereagainst the minor tongues 9. These minor tongues 9 are of such dimension that in the inward fold there is effective closure of the V-cut cuts 10, and as so closed stitching 20 not only assembles a pair of tongues with each other but anchors such tongues with the disk 18 in bringing the sides of the adjacent tongues 9 into abutting relation. There is thus established a curved or circular contour for the head at the base of this container.

The opposite end has the tongues 12, 13, 14, upwardly projecting as the container has open top and is in position to be charged. As there is

flowed into this container the material, whether granular, liquid or molten, at the full charge the tongues may be in opposite pairs laid toward each other. Preferably the tongues having the scorings 5, 6, thereacross are the first pair of opposite tongues to be laid down. The next pair of tongues may include the tongue portions 13, 14, having the seam thereacross. In the hexagonal set-up this will leave a third pair of tongues to be the last or outer pair as completing the sealing overlapping, and as their ends may to some extent overlap, stitching 21 is a holding of this outer flap pair in flat position across this second head or top. In this anchoring by the stitching 21, the tool for these wire staples may be thrust into position on opposite sides of the flaps as stapled and thus insure an efficient anchoring. These flaps as having the coating 19 on the inner side provide this non-adherent face as exposed to the poured asphalt 22 as close thereagainst.

Notwithstanding the weight of a substance as poured asphalt, the strength of the seam 15 as held by stitching 16 is sufficient for charging of the container as standing alone. As the pour of asphalt approaches the top, there is of course less load and the widened stitching 17 is sufficient for holding in the top region. The fact that the scorings 5, 6, are away from the tongues at this overlapping tongue head or top is an additional factor that there is not a weakening for the contents to soak in or penetrate the fiber or box board paper. The scores 5, 6, in opening to approach a cylinder in the instance of the coating 19 adopted herein, do not tend in such flexure to fracture. There is absence of scoring toward polygonal head portion adjacent the base of the several tongues 12. However, the base portions of these several tongues approach straight lines and thereby cause this can-shaped cylindrical charged body to flex toward the corners of the polygon with absence of definite defining thereof to the extent which would introduce a weakened corner. There is thus no weakened corner for outside severe abrasion. There is not sufficient flexure to detract from continuity of the coating 19 on the inside. The resulting container is one which may be readily rolled as on its side in the approaching-cylindrical form, but in this rolling there is 50

5 condition of stability to retain a position against rolling unless caused to shift therefrom. This stable condition is due to the configuration as departing from cylindrical form at the polygon-approaching head end or top.

10 The fact that the fiber of the stock runs lengthwise gives flexibility for approaching cylindrical form and stiffness against crushing between the heads. Accordingly, with these containers in the region of 22 to 36 inches high and 13 to 15 inches in diameter, they may be charged with asphalt up to the neighborhood of 50 to 100 pounds and stacked on end for as many as three or four courses high. This is a 15 position of stability for storage or transportation.

20 As the purpose is one for opening one of these containers, the flaps 12 may be readily torn and opened out for pouring the contents in the event it be granular, while if it be congealed into a body, as asphalt, there may be a stripping of the container therefrom or other removal, depending on whether or not the receptacle be for single service.

25 In the instance of Fig. 7, there is shown octagonal flaps or tongues 23 instead of the hexagonal flaps or tongues 12 in the approach to regular polygonal form for one end of the vessel, herein defined as the top.

30 What is claimed and it is desired to secure by United States Letters Patent is:

35 A two part container, polygonal at one end and circular at the other, one of said two parts of the container being a disk closure for the circular end of the container, the other of said two parts being a tubular body having at one end an annular series of minor tongues overlapping the disk with the body cylindrical contour thereabout, and major tongues at the other end of the body for the free ends of said latter tongues to overlap and the bases of said latter tongues to define sides of a polygon with the corners of the polygon lying substantially in the cylindrical surface of the cylindrical extension 40 defined by said disk, said cylindrical contour sufficiently persisting for rollability of the charged container, and the polygon being sufficiently pronounced for stability against free rolling of the container on its side and at rest.
